UNITED STATES PATENT OFFICE

169,453

CLOCKCASE

Carl Otto, New York, N. Y., assignor to General
Electric Company, a corporation of New York

Application February 16, 1953, Serial No. 23,632

Term of patent 14 years

(Cl. D42—7)

To all whom it may concern:

Be it known that I, Carl Otto, a citizen of the United States, residing at 745 Fifth Avenue, New York city, in the county of New York, State of New York, have invented a new, original, and ornamental Design for a Clockcase, of which the following is a specification, reference being had to the accompanying drawing, forming a part thereof.

In the drawing:

Fig. 1 is a front perspective view of a clockcase showing my new design;

Fig. 2 is a side elevational view; and

Fig. 3 is a top plan view.

I claim:

The ornamental design for a clockcase, as shown.

CARL OTTO.
